UNITED STATES PATENT OFFICE.

EDWARD A. HEMPHILL, OF JERSEY CITY, NEW JERSEY.

INDEX AND SYSTEM OF INDEXING.

Application filed June 9, 1922. Serial No. 567,060.

The invention relates to novel and useful improvements in a card indexing system, and more especially to novel and useful classifying and identifying means embodied in or with the cards.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a top plan, looking at a group of cards downwardly and backwardly at an angle of approximately forty-five degrees;

Fig. 2 shows an index card marked for a class and sub-class, in particular, for the month and day of the month to indicate a sub-class group;

Fig. 3 is a class-indicating card, in particular, a month-indicating card;

Fig. 4 is a data card, showing one application thereof, and indicated for class and sub-class by the cards of Figs. 2 and 3;

Fig. 5 is a view similar to Fig. 1, showing in particular alphabetical classes and sub-classes;

Fig. 6 shows an index or indicating card, marked for class and sub-class; and

Fig. 7 shows a corresponding data card.

The invention relates to indexing devices and to a card index system incorporating or embodying said devices, the term "card index" being used in a sense sufficiently broad to cover library cards, other kinds or forms of cards, loose data or other information bearing sheets, books and the like.

The invention is preferably, and in some of its features essentially embodied in that type of index wherein the cards have portions cut away to indicate classification and sub-classification, such cut-out portions cooperating with certain index cards for indicating classes and sub-classes, and which

are visible through, or are indicated by, these cutout portions of the cards.

In the exemplary embodiment of Figs. 1 to 4, the invention is shown applied to a set of cards, the class and sub-class marks or notches indicating the months and the days of the month on the respective cards. In Fig. 1 are shown the first three and the last three days of January; the first two and the last day of February; and some of the days in the month of December, the intervening parts being broken away.

The ordinary cards, that is, the classified information-bearing cards 1, are provided with a class-indicating notch or cut-away portion 2 and a sub-class indicating or cut-away portion 3. The two notches are of different sizes, preferably, so as visually to differentiate between the class mark or cut-away portion and the sub-class mark or cut-away portion. The notches are preferably V-shaped, or otherwise narrowing from the top toward the bottom, so as to strengthen the cards and prevent breakage thereof alongside the notch, to which damage the cards are very liable with square notches or openings, or other forms thereof which are wide at the bottom.

Preferably there is printed on each card words, figures, or other marks or symbols indicating both the class and the sub-class. In Figs. 2 and 4 the months, which in this case is the class, are printed in a second or lower row 4, the corresponding class or month indicating notch 2 being in alignment vertically with the name of the particular month indicated by the card shown, and if desired, cutting thereinto, as shown at 2. If desired, the name of the month may be also printed in the center or elsewhere, on the card, as shown at 5, although this is unnecessary.

There may be like markings for the sub-class, in this case the days of the month, as shown at 6, this line of numbers being preferably arranged above the class-indicating line, in this case the months, for the reason that the sub-class or day indicating notch is shallower than the month indicating notch. The markings for the sub-class are arranged differently for different cards, as shown, for example, in Figs. 1 and 2, in order to allow sufficient space to prevent the use of particular sub-classes immediately above a particular main class, since the deep

notch for the main class should not cover the sub-class notch.

In Fig. 4, the use of data or information upon the card 1 in connection with the indicating means is shown, and its application to various cards, loose-leaves and the like, will be readily understood.

In cooperation with the cards marked as described, index cards are provided both 10 for the classes and sub-classes. The class index card 8 is shown in Fig. 3, and the class indicating notch 2 therein indicates the month of March. In the case of this card, however, as preferably employed, this 15 card is used to indicate the month of February and the notch 2 in alinement with the cards for March is cut-away to provide a ready sight along the alined notches or cut-out parts of the March cards.

20 The particular card shown in Fig. 3 is shown also near the center of Fig. 1, the word "Feb." thereon being in alinement with the notches for February in the February cards in front of this card 8. Thus in usual 25 practice, the class-indicating or guide card has the class designation printed thereon in alinement with the class notch in the corresponding data or indexed cards, this card being notched in alinement with the class 30 notch for the succeeding class simply to provide a clear view for the next class. The index card 8 for January and that for December are also shown in Fig. 1.

The index card 9 for the sub-classes, as 35 preferably embodied, is shown in Fig. 2 of the drawings, and also a plurality of these are shown in their relation to the other cards in Fig. 1. These sub-class cards are preferably provided with the class and sub- 40 class notches or markings 2 and 3, the class notch 2 in these cards being in alinement with the corresponding class notches in the data or other indexed cards, but the sub-class notch is in alinement with the next 45 sub-class beyond or to the rear, similarly to the class notch in the class index cards.

In Figs. 5, 6 and 7, the invention is shown applied to a classification under the letters of the alphabet, and sub-classification also 50 under the letters of the alphabet, but the same general description will apply thereto. In Fig. 6, the class-indicating card 8^a corresponds to card 8 of Fig. 3, and in Fig. 7, the information-bearing card 1^a corresponds 55 to card 1 of Fig. 4.

The classifications shown in these figures is under the letters of the alphabet as classes, and also as sub-class groups under both A and B. The cards are sub-classified 60 from A to F, from G to K, from L to M, from Q to R and from S to Z. The arrangement here is entirely similar to that already described, and will be apprehended fully without further detailed description.

65 It will be understood that changes may

be made from the details herein shown and described, within the scope of the accompanying claims, without departing from the principles of the invention, and without sacrificing its chief advantages.

What I claim is:—

1. An index system comprising a plurality of index cards or sheets arranged in classes and sub-classes, said cards having notches of one size and depth positioned to indicate 75 particular classes, and notches of another size and depth positioned to indicate particular sub-classes, and index marks on each card cooperating with the notches.

2. An index system comprising a plurality of index cards or sheets arranged in classes and sub-classes, said cards having notches of one depth positioned to indicate particular classes, and notches of another depth positioned to indicate particular sub-classes, and 85 index marks on each card cooperating with the notches.

3. An index card having two rows of indicia at different levels near the top thereof, and having a relatively deep notch cooperating with an indicium in the lower row and a shallower notch cooperating with an indicium in the upper row.

4. A card index system for a plurality of 95 classes comprising a plurality of cards for each class, each of which is provided with an aligning class-indicating notch, and a class index card for each class which is provided with a notch out of alinement with the notches of the cards in its class.

5. A card index system for a plurality of classes comprising a plurality of cards for each class, each of which is provided with an aligning class-indicating notch, and a class index card for placement at the rear 105 of the cards of each class, and provided with a notch out of alinement with the notches of the cards of its class.

6. A card index system for a plurality of 110 classes comprising a plurality of cards for each class, each of which is provided with an aligning class-indicating notch, and an indicia-bearing class index card for each class for placement at the rear of its class, whereby one of the indicia thereon is visible 115 along the groove formed by the notches in the cards of its class, said class index card being provided with a notch in alinement with the class-indicating notches in the following class.

7. A card index system divided into classes and sub-classes, the cards in a class being each provided with alined class-indicating notches, and being further provided with alined sub-class indicating notches, and 125 guide cards for the classes and sub-classes which are placed at the rear of their own classes and sub-classes and which bear indicia readable along the class and sub-class grooves formed by the notched cards.

8. A card index system divided into classes and sub-classes, the cards in a class being each provided with alined class-indicating notches, and being further provided 5 with alined sub-class indicating notches, and guide cards for the classes and sub-classes which are placed at the rear of their own classes and sub-classes and which bear indicia readable along the class and sub-class 10 grooves formed by the notched cards, the guide cards being provided with class and sub-class indicating notches in alinement with the class and sub-class notches of the cards in the adjacent succeeding group of 15 cards.

9. A card index system divided into classes and sub-classes, all the cards of a particular class being notched in their upper edges at the same place, and all the cards of

a particular sub-class being again similarly 20 and correspondingly notched in their upper edges but at a different place, the cards having indicia marked thereon along their upper edges for determining the placement of the two notches, and guide cards having 25 similar indicia marked thereon along their upper edges for placement at the rear of a class or sub-class, each of the guide cards having class and sub-class notches in its upper edge registering with the class and 30 sub-class notches of the succeeding class or sub-class, leaving its own class and sub-class indicia clear and readable through the grooves formed by the class and sub-class notches of its own group. 35

In testimony whereof, I have signed my name to this specification.

EDWARD A. HEMPHILL.
